(57) **CLAIM**

The ornamental design for a bar shaped light, as shown and described.

DESCRIPTION

FIG. 1 is an isometric top, left front view of a BAR SHAPED LIGHT according to a first embodiment;

FIG. 2 is an isometric top, right rear view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is an isometric top, left front view of a BAR SHAPED LIGHT according to a second embodiment;

FIG. 10 is an isometric top, right rear view thereof;

FIG. 11 is a front view thereof;

FIG. 12 is a rear view thereof;

FIG. 13 is a right side view thereof;

FIG. 14 is a left side view thereof;

FIG. 15 is a top view thereof; and

FIG. 16 is a bottom view thereof.

The evenly spaced broken lines in the drawings depict portions of the embodiments of the BAR SHAPED LIGHT which form no part of the claim.
